(57) **CLAIM**

The ornamental design for a universal model display stand, as shown and described.

DESCRIPTION

FIG. 1 is a top-front-left perspective view of a universal model display stand showing my new design;

FIG. 2 is a bottom-rear-right perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right elevational view thereof;

FIG. 8 is a left elevational view thereof;

FIG. 9 is a left elevational view thereof, wherein the universal model display stand is shown in a resting configuration; and,

FIG. 10 is a left elevational view thereof, wherein the universal model display stand is shown in a propping configuration.

The broken lines showing a model car in FIGS. 9 and 10 are included for the purpose of illustrating environmental structure and form no part of the claimed design.

1 Claim, 10 Drawing Sheets
